US00D995956S

(12) **United States Design Patent** (10) **Patent No.:** **US D995,956 S**
Li (45) **Date of Patent:** **** Aug. 15, 2023**

(54) **TRANSMITTER OF DOG TRAINING COLLAR**

(71) Applicant: **SHENZHEN PATPET TECHNOLOGY CO., LTD.**, Shenzhen (CN)

(72) Inventor: **Linxian Li**, Shenzhen (CN)

(**) Term: **15 Years**

(21) Appl. No.: **29/819,450**

(22) Filed: **Dec. 15, 2021**

(51) **LOC (14) Cl. 30-99**

(52) **U.S. Cl.**

USPC **D30/199; D10/104.1**

(58) **Field of Classification Search**

USPC ..... D30/151–155, 144, 199, 160; 119/792–798, 850, 855–859, 654, 905, 119/907, 815, 712, 802, 784, 769, 760, 119/776, 862, 908, 860, 719–721; 242/381.1–381.2, 385.4, 378.3, 376.1, 242/385.1, 916, 601, 570, 405, 404, 371, 242/223, 170, 388.1, 405.2, 377, 381.3, 242/381.6, 405.3, 388.6, 384.7, 382, 242/396.1, 404.1, 380; 362/108; 33/767, 33/769, 414; D12/400; D3/229, 230, D3/207, 208, 215; 40/1.5, 455, 640, 303; 206/63.3, 459.5, 702, 408; D6/515; D8/358, 360, 347, 360.1, 359, 356, D8/DIG. 1; D24/145, 167, 186, 146, 169; D10/57, 72, 106.1, 104.1, 104.2, 109.2, D10/70, 97, 98, 78, 65; D20/28; 224/666, 678; 16/445; 283/74, 70; D11/232, 200, 216, 1, 2, 86, 87, 201, D11/206–210, 212–215, 218; 24/163 K, 24/122.3, 323, 702, 600.4–600.7, 163 R, 24/169–171, 173, 177–179, 191, 194, 24/195, 197, 200, 303, 616, 635, 313, 24/615, 3, 6, 3 K, 599.2, 96, 221, 237, 24/311, 312, 314, 321, 338, 339, 309;

CLAIM

The ornamental design for a transmitter of dog training collar, as shown and described.

DESCRIPTION

FIG. 1 is a front view of a transmitter of dog training collar, showing my new design;
FIG. 2 is a top plan view thereof;
FIG. 3 is a bottom plan view thereof;
FIG. 4 is a rear plan view thereof;
FIG. 5 is a left plan view thereof;
FIG. 6 is a right plan view thereof; and,
FIG. 7 is a perspective view thereof.
